OF NEW YORK, N. Y., A CORPORATION OF DELAWARE

GAS-COOLING APPARATUS

Application filed April 14, 1927. Serial No. 183,633.

The present invention relates to heat exchangers, and more particularly to apparatus for cooling gases in which the gas to be cooled is passed over the exterior surfaces of a bank or bundle of tubes through which a liquid, such for example as water is circulated.

In numerous installations of gas cooling apparatus, such for example as in the cooling of electric generators by the circulation of air, hydrogen, or other gas in closed circuit through the generator and gas cooler, it is important that the gas be forced through the cooling apparatus at relatively high velocity. This relatively high velocity is important in a closed circuit generator air cooling system because of the necessity of reducing the volume of air or other gas to a minimum, so as to reduce the possibility of explosion, and the damage resulting in case an explosion should occur.

It is also desirable to employ in such heat exchangers, metal tubes having relatively thin walls so as to save in cost of manufacture. In order to suit the space requirements in certain installations, convenience demands that the exchangers be made of considerable length as compared to the lateral dimensions of the bank of tubes. Long tubes also assist in reducing the cost. Hence relatively long, as well as relatively flexible, tubes are desirable. Even in apparatus having comparatively rigid tubes, the passage of gas over them at high velocity tends to cause undesirable vibration of the tubes, and with long relatively flexible tubes the tendency to vibrate is much increased.

In this type of heat exchanger, furthermore, it is particularly desirable to provide a construction which will insure to the greatest possible degree against the leakage either of the gas from the shell of the exchanger, or of the water from the tubes. To do this it is highly important to reduce to negligibility, if possible, the stresses tending to

loosen the tubes from the tube sheets which are set up by the forces of expansion and contraction. In the case of a generator gas cooler for example, the tubes are subjected to relatively wide differences in temperature, and the cooler may be operated for a considerable period of time at one temperature, and then comparatively suddenly, be operated for another considerable period of time at a substantially higher or a substantially lower temperature. This occurs for example when a generator which may be operating at say 50% of normal load, is operated at from 125% to 200% of normal load during the peak hours.

Accordingly the principal object of the present invention is to provide an apparatus of improved construction for extracting the heat from the air or other gas which has been circulated through an electric generator for the purpose of cooling the same.

Another object of the present invention is to provide a gas cooler in which there will be little, if any, vibration of the tubes of the cooler even when the gas is passed through the cooler at relatively high velocity.

Another object of the invention is to provide a gas cooler in which the possibility of leakage not only of cooling liquid, but also of gas, is reduced to the greatest possible extent.

A further object of the invention is to so construct a gas cooling apparatus that the tendency of the tubes to become loosened at their connections with the tube sheet shall be negligible.

A still further object of the invention is to so improve the construction of apparatus for transferring heat between liquid and a gas as to reduce the cost of manufacture of such apparatus.

In the accompanying drawings, I have illustrated by way of example one embodiment of the invention. In these drawings

Fig. 1 is a longitudinal section taken verti-

cally and centrally through a generator gas cooler;

Fig. 2 is an end view looking from the left of Fig. 1;

Fig. 3 is a vertical section taken on the broken line 3—3 of Fig. 1 showing in its upper portion the fins in position on the tubes, and in its lower portion the spacing blocks at the centers of the tubes;

Fig. 4 is an elevation of a spacing block clamped upon a pair of tubes;

Fig. 5 is a section taken on line 5—5 of Fig. 4; and

Fig. 6 is a section taken on line 6—6 of Fig. 2.

Referring now to the accompanying drawings, the improved gas cooling apparatus comprises a casing or shell 1 closed at both sides as shown in Fig. 3 and open at the top and bottom. The shell is provided along its top and bottom edges with suitable flanges for connecting with the air or gas duct of an electric generator cooling system, the duct leading from the generator and carrying the warm or hot air to the cooling apparatus being connected at the top, and the duct leading to the generator and returning the cooled air thereto being connected to the cooling apparatus at its bottom. The sides of the shell 1 are preferably provided with vertical struts 2 for stiffness.

Flanges 3 are provided at the ends of the shell to which the tube sheets 4 are securely clamped by means of collar bolts 5 (Fig. 6).

The tubes 6 are expanded at their ends into the tube sheets 4 and are arranged in parallel horizontal rows (Figs. 1 and 3). The tubes are provided with metal fins 7 which are threaded in closely spaced relation upon the tubes. The close relationship of the fins may be seen in Fig. 5, and a convenient method of manufacture is to provide the fins with circumferential, or partially circumferential, bases 7^a (Fig. 5) which serve both to aid in securing a good heat conductivity between the surface of the tubes and the fins, and in automatically spacing the fins uniformly by the desired amount.

The fins are of relatively thin sheet metal and are of elongated shape so as to span two or more tubes in a horizontal row as is to be seen in Fig. 3. The tubes themselves are also of relatively thin material. A convenient size tube is made from No. 18 B. W. G. copper stock and is approximately 1" in outside diameter and about 12 feet in length. A tube of these dimensions and material is relatively flexible and sags under its own weight to a substantial extent when the tubes are supported in the tube sheets without any intermediate support. The extent of the natural sag or bow at the centers of tubes of this length and character is approximately 3".

Even though both the tubes, and the fins are relatively flexible by themselves, when

the elongated fins are assembled upon the tubes in closely spaced relation as indicated in Figs. 1 and 5, and with the fins secured to two or more tubes, the tubes thus secured together are rendered substantially rigid in the common plane passing through the axes of these tubes, but flexibility in the plane at right angles to this common plane is substantially unimpaired.

The water is caused to pass through the tubes by means of caps or heads 10 and 15 placed respectively on the left and right tube sheets. Cap 10 is divided by horizontal partitions 12 into four full width lateral compartments 14, and cap 15, subdivided by horizontal partitions 16 into three lateral chambers. Hence in the example illustrated the water which enters at the inlet 11 in cap 10 makes six passes through the apparatus before leaving at the outlet 13.

The caps 10 and 15 are clamped against their respective tube sheets by means of the collar bolts 5 (Fig. 6). These bolts, as shown in this figure, each have a collar rigidly secured to the bolt midway between its ends. By the use of these collar bolts either or both of the caps can be readily removed for the purpose of inspecting or repairing the tube joints, without loosening the tube sheets with respect to the flanges 3. This is an essential feature of construction when the gas which is within the interior of the shell is of an explosive, poisonous or obnoxious character, or where the gas is valuable. The caps can be removed without fear of permitting the gas to leak from the shell at the tube sheet joints.

It will be remembered that the tubes in each horizontal row are restrained against lateral or horizontal movement by means of the elongated fins which are secured to a plurality of tubes in each horizontal row. The tubes are rendered substantially rigid in the plane of the major dimension of the fins. The fins are shown as being secured to only two adjacent tubes inasmuch as it is extremely convenient to manufacture the heating elements in this way.

It is well known that when a resilient attenuated body, such for example as a reed, is supported to permit freedom of motion or vibration in a given plane, the body can be set in vibration through the influence of even a relatively low velocity stream or current of air which is directed over the body at right angles to the plane of its freedom of motion. In accordance with the present invention the tubes in each row are restrained against lateral movement in the common plane passing through these tubes by means of the finned construction, and the air or gas is directed through the gas passage of the cooling apparatus over the surfaces of the tubes at right angles to this plane, as indicated by the arrows in Fig. 1. The gas is circulated over the tubes and through the generator windings by

means of a suitable fan (not shown) which is placed in the usual ducts or conduits connecting the two pieces of apparatus.

When the stream of gas is directed substantially at right angles to the plane of rigidity, vibration of the tubes is very greatly reduced, and in most cases entirely eliminated because of the rigidity imparted to the tubes by the closely spaced fins spanning two or more tubes. The tendency to vibrate which is present in tubes that are relatively rigid, such for example as tubes having thick walls, or relatively short tubes, is materially reduced by employing this construction.

As was mentioned above, the tubes which are preferably used in the gas cooler of the present invention, have relatively thin walls and are of considerable length so that they are relatively flexible and have considerable natural sag. According to the invention, tubes of this character are mounted in the tube sheets in such manner as to preserve the natural sag. That is, the tubes are not subjected to initial tension in order to straighten them. It will be understood from Fig. 1 of the accompanying drawings that the tubes are installed in this manner, the curvature indicated being that which is the result of the sagging of the tubes under the influence of gravity. The tubes are provided with spacing members 8 which are arranged in a vertical tier midway between the tube sheets. The spacers 8 are of such vertical dimensions as to space the horizontal rows of tubes apart sufficiently to prevent contact or interference between the fins of adjacent rows. A bar 9 extends transversely from side to side of the casing in contact with the spacing members of the lowermost horizontal row of tubes and serves as a rigid support for the entire tier.

The details of construction of the spacing members 8 are shown in Figs. 4 and 5 which show these members as made in complementary upper and lower halves having partially circular recesses for clamping over a pair of horizontal tubes. These halves are held in clamped relation to the tubes by means of a rivet or bolt 8^a. The spacing blocks may be secured to individual tubes if desired, but it is more convenient to make them of sufficient length to span at least two tubes because they can be readily clamped in place by the use of a single clamping rivet or bolt.

It will be understood that from the manufacturing standpoint it is preferable, when the apparatus is cold, to have the spacing members 8 in a given tier in contact, or substantially in contact, with one another so that the centers of all of the tubes of the tube bundle or bank are firmly supported by the bar 9. Under these conditions when the apparatus is placed in operation, and the metal of the tubes is heated by the passage of the gas over them, the resulting expansion of the

tubes causes the tubes to bow downwardly between the tier of spacing blocks 8, and each of the tube sheets. Thus the already sagging tubes bow or flex in a plurality of nodes throughout their length intermediate the tube sheets, and even though the tubes are held firmly at their centers against downward movement, and laterally throughout their entire length against lateral movement, nevertheless the stresses tending to loosen the tubes from the tube sheets are effectively removed. For this reason leaks at the joints of the tubes with the tube sheets are not likely to occur.

I should regard tubes arranged so that their spacing blocks 8 do not quite contact with one another when the tubes are cold, but which do come into contact when the tubes are heated, as being within my invention if the tubes bow in a plurality of nodes when the tubes are heated further.

With very long tubes, such for example as tubes over about 15 feet in length, it is desirable to provide two or more tiers of spacing blocks 8 and transverse bars 9, and with this construction the tubes will bow in three or more nodes instead of two as in the example shown in the drawings. By passing the gas over the tubes from top to bottom in the direction of the arrows the pressure of the gas tends to hold the spacing blocks firmly in contact with one another, and the lowermost block against the bar 9. This relieves the tube sheet joints of a certain amount of stress which would be present if the air were forced through the apparatus in the opposite direction, and this stress would be largest in the upper tubes of the bank.

While I have illustrated my invention in connection with a heat exchanger in which the lateral rigidity is imparted to the tubes by means of fins which span a plurality of tubes, it is to be understood that the lateral rigidity may be secured in other ways, and the tubes may be provided with fins which are mounted upon individual tubes only, or the tubes may have no fins at all. Thus the lateral stiffness may be provided by the spacing blocks, particularly if the ends of the blocks, as shown in Fig. 3, are made to touch each other. If still greater lateral rigidity is desired, means may be provided on the sides of the shell of the exchanger for engaging the outer ends of the outer supporting blocks in each row.

It is also to be understood that, when relatively flexible tubes are employed, it is not necessary that they be given just the natural sag which they assume when supported only at their ends, and no more or no less. With flexible tubes the extent of bowing may be increased or diminished above or below the natural sag, depending upon convenience in manufacture, as long as there is sufficient

bowing to relieve the stresses at the tube sheet joints under expansion and contraction.

It will be understood from the above that when the gas is forced over the tubes, which in many installations may be at relatively high velocity, the passage of this gas tends to set the tubes vibrating. This tendency to vibrate is by far the greatest in the horizontal or lateral direction, and is effectively prevented by the lateral rigidity imparted by the fins. The air passing the tubes at right angles to this plane of rigidity produces little, if any, vibration in the tubes. The tendency to vibrate vertically which is produced by the passage of the air over the tubes is eliminated by causing the tubes to assume a natural bow shape in the direction of movement of the air, and by the support afforded by the one or more tiers of spacing blocks 8. The provision of a natural bow of the tubes in the direction of movement of the air also assists in reducing the tendency of the tubes to vibrate laterally, since a straight tube, or a tube which is bowed in the opposite direction to the movement of the air is in relatively unstable equilibrium as compared to a tube which is bowed in the direction of the air movement, and therefore vibrates more readily.

30. I claim:

1. In a heat exchanger comprising a bank of relatively flexible tubes secured at their opposite ends to a pair of tube sheets, means for restraining the tubes throughout their length against lateral movement in a given plane, and means for restraining their lateral movement in any direction at one or more points intermediate the ends of the tubes so as to cause each tube to bow in a predetermined direction in a plurality of nodes under the influence of the forces of expansion and contraction.

2. In a heat exchanger, a bank of relatively flexible tubes, tube sheets into which the tubes are secured at their ends, said tubes being arranged in substantially parallel rows, fins mounted in closely adjacent relation throughout the length of said tubes, each fin spanning a plurality of tubes in a row and rendering the tubes substantially rigid in the planes of said rows, and means for restraining the tubes against movement at right angles to said planes at one or more points intermediate the ends of the tubes so as to cause the tubes to bow in a plurality of nodes under the influence of the forces of expansion and contraction.

3. In a heat exchanger, a bank of relatively flexible tubes, tube sheets into which the tubes are secured at their ends, said tubes being arranged in substantially parallel rows, fins mounted in closely adjacent relation substantially throughout the length of said tubes, each fin spanning a plurality of tubes in a row and rendering the tubes substan-

tially rigid in the planes of said rows, spacing members secured to the tubes of each row and arranged in a tier substantially perpendicular to the axes of the tubes, and a support fixed at the bottom of the bank of tubes for engaging the spacing members of the bottom row of tubes, the said spacing members engaging with one another and with said support to maintain the tubes in spaced parallel relationship and to cause each tube to bow in a plurality of nodes under the influence of the forces of expansion and contraction.

4. In a heat exchanger, a bank of slender flexible tubes, tube sheets into which the tubes are secured at their ends, said tubes being arranged in parallel rows, fins secured to the tubes in closely spaced relation throughout the length thereof, each fin spanning a plurality of tubes in a row and restraining the tubes against lateral movement throughout their length in the plane of said row, and means for passing a stream of gas over the surfaces of said tubes in a direction substantially at right angles to the plane in which said tubes are restrained against lateral movement.

5. In a heat exchanger, a pair of tube sheets, a plurality of slender flexible heat transfer tubes secured at their ends in said tube sheets, means for rendering said tubes substantially rigid in one direction throughout their length, said tubes being initially bowed in a direction at right angles thereto, means for engaging the tubes at a point intermediate their ends for maintaining said point in fixed position, and means for passing gas to be cooled over said tubes in the direction in which said tubes are bowed.

6. In a heat exchanger, a bank of slender flexible thin-walled tubes, tube sheets into which the tubes are secured at their ends, said tubes being arranged in substantially parallel rows, fins mounted in closely adjacent relation substantially throughout the length of said tubes, each fin spanning a plurality of tubes in a row and rendering the tubes substantially rigid in the planes of said rows, spacing members comprising pairs of complementary blocks laterally applied to the tubes and being arranged in a tier substantially perpendicular to the axes of the tubes, and a support fixed at the bottom of the bank of tubes for engaging the spacing members of the bottom row of tubes, said spacing members engaging with one another and with said support to maintain the tubes in spaced parallel relationship and causing each tube to bow in a plurality of nodes under the influence of the forces of expansion and contraction.

7. A heat exchanger element comprising a pair of slender flexible thin-walled tubes having heat radiating fins secured in closely adjacent relation substantially throughout
